DAYTON ULREY, OF PITTSBURGH, PENNSYLVANIA, ASSIGNOR TO WESTINGHOUSE ELECTRIC & MANUFACTURING COMPANY, A CORPORATION OF PENNSYLVANIA

VACUUM TUBE DEVICE

Application filed November 5, 1925. Serial No. 66,979.

My invention relates to space current devices, and particularly to vacuum tubes having a metal shell as an integral part of the container.

5 An object of my invention is to provide strengthening and protective means for the metal shell portion of a power vacuum tube.

Another object of my invention is to provide an electrodeposited protective covering 10 upon the metal shell portion forming the external anode of a vacuum-tube device.

In prior art of vacuum tubes it has been customary to construct high-power vacuum tubes with a vapor tight metal shell portion, 15 adapted to serve simultaneously as anode and having sealed thereto an insulating closure adapted to support other electrodes.

Difficulty has been encountered in the 20 evacuation of such device because of an undue oxidation of the outer metal surface of the shell, during the baking out which is incidental to the evacuation of the device and also because of the tendency of the thin metal shell to collapse by external pressure at the 25 baking temperature.

My invention provides a strengthening and protecting means for the metal shell portion, which consists of an electrically deposited layer of another metal of greater strength 30 and having greater resistance to oxidation.

Other objects and structural details of my invention will be apparent from the following description, when read in connection with the accompanying drawing, in which

35 The single figure is a view in vertical elevation of a preferred embodiment of my invention.

The vacuum-tube device of my invention 40 consists of a metal shell portion 1, which may be of copper, and a glass portion 2 attached thereto by a seal 3. Suitable electrodes are positioned within the shell portion 1 as shown by the dotted lines in the drawing. Upon the outer surface of the metal shell portion 1 45 is a coating 4 of a stronger, more resistant metal, which may be iron, or of iron with a coating of nickel thereover.

In the construction of my device, the metal shell portion 1 and the glass closure 2 are 50 prepared in the usual way. The seal between

them is then produced in the customary manner by fusion to, and working over of the glass upon the edge of the metal shell 1. The contained electrodes may be inserted at this point or may be inserted later in the usual 55 way. The assembly comprising the metal shell 1, the glass portion 2 and the seal 3 may then be treated in an electro-deposition bath whereby a coating of electrically deposited iron 4 is caused to cover the metal 60 shell portion 1 up to but not within or over the seal 3. Following the completion of the iron coating a second coating of nickel may be similarly added, if desired.

In the operation of exhausting, the device, 65 which may be placed in an oven in which a temperature in the neighborhood of 500° C. may be obtained, is connected by a pump leading to the evacuating system. Simultaneously, electrical connections are made to 70 the filament and anode circuits in order that electron bombardment may be applied to the anode. The temperature of 500° C. is below that at which the glass portion of the device begins to soften, and therefore, the 75 glass closure is not subject to destructive forces. The operation of electron bombardment, however, may raise the temperature of the metal shell portion, which is the anode, to a temperature in the neighborhood of 80 800° C.

This temperature appears to be necessary 85 in order to evolve all of the occluded gases but is above the temperature at which copper begins to lose its physical strength and, therefore, the copper shell would tend to collapse in the absence of the reinforcing coating 4. Also, the temperature is one which in the absence of the protecting coating 4 would be 90 sufficiently high to cause the copper to tend toward rapid oxidation and thus remove metal from the thin portion near the seal to such an extent as may allow the copper shell to collapse at this point under the atmospheric pressure, or even cause an actual perforation because of removal of metal.

The presence of the electrically deposited coating of my invention however, counteracts 95 this tendency. It furnishes sufficient additional strength to prevent the collapse of the 100

copper and it furnishes sufficient resistance to oxidation to prevent the removal of undesirable quantities of metal from the shell by oxidation and scaling.

5 By this means, I have produced a vacuum-tube device having much greater physical strength, which is much more resistant to corrosion and to pressure, and is much more convenient to manufacture.

10 While I have shown but a single embodiment of my invention, it is capable of other changes and modifications therefrom and it is desired, therefore, that only such limitations shall be imposed thereon as are required 15 by the prior art or indicated by the appended claims.

I claim as my invention:

1. The process of removing occluded gases from an outer metallic shell which acts as an 20 electrode in a vacuum tube which comprises coating the exterior of said shell with a second metal resistant to oxidation and then heating said shell in an atmosphere containing oxygen to such a temperature that said 25 metallic shell begins to lose its mechanical strength.

2. The process of removing occluded gases from an outer metallic shell which acts as an electrode in a vacuum tube which comprises 30 coating the exterior of said shell with a second metal resistant to oxidation and then heating said shell in an atmosphere containing oxygen to a temperature in the neighborhood of 800° C.

35 3. The process of removing occluded gases from an outer copper shell which acts as an electrode in a vacuum tube which comprises coating the exterior of said shell with a second metal resistant to oxidation and then 40 heating said shell in an atmosphere containing oxygen to a temperature in the neighborhood of 800° C.

4. The process of removing occluded gases from an outer metallic shell which acts as an 45 electrode in a vacuum tube, the steps which comprise coating the exterior of said shell with a second metal having a higher melting point than has the material comprising said shell, and then heating said shell to such a 50 temperature that said metallic shell begins to lose its mechanical strength.

5. A vacuum tube device comprising a glass portion, a vapor-tight copper shell portion sealed thereto by means of a fused seal 55 and acting as an exterior electrode, an interior electrode cooperating therewith and a coating of another metal on said vapor-tight copper shell portion, said metal coating being of greater mechanical strength than said 60 copper.

6. A vacuum tube device comprising a glass portion, a vapor-tight copper shell portion sealed thereto by means of a fused seal and acting as an exterior electrode, an 65 interior electrode cooperating therewith and a

coating of another metal on said vapor-tight copper shell portion, said metal coating having greater resistance to oxidation than said copper.

7. A vacuum tube device comprising a 70 glass portion, a vapor-tight copper shell portion sealed thereto by means of a fused seal and acting as an exterior electrode, an interior electrode cooperating therewith and a coating of another metal on said vapor-tight 75 copper shell portion, said metal coating being of greater mechanical strength and having greater resistance to oxidation than said copper.

80 In testimony whereof, I have hereunto subscribed my name this 23rd day of October, 1925.
